UNITED STATES PATENT OFFICE.

THOMAS O'DONNELL, OF IRONWOOD, MICHIGAN.

DESIGN FOR AN ELECTRIC-LIGHT FIXTURE.

50,138.

Specification for Design.

Patented Jan. 2, 1917.

Application filed April 7, 1916. Serial No. 89,718. Term of patent 14 years.

To all whom it may concern:

Be it known that I, THOMAS O'DONNELL, a citizen of the United States, residing at Ironwood, county of Gogebic, and State of Michigan, have invented a new, original, and ornamental Design for an Electric-Light Fixture, of which the following is a specification, reference being had to the drawing, forming a part thereof.

Figure 1 is a side elevation of a fixture

embodying the invention, and, Fig. 2 is a top plan view of the same.

I claim:

The ornamental design for an electric light fixture, as shown.

THOMAS O'DONNELL.

Witnesses:

JAS. A. SULLIVAN,
ELIZABETH CLARA O'DONNELL.
